(74) Attorney, Agent, or Firm—Akerman Senterfitt

(**) Term: **14 Years**

(57) **CLAIM**

(21) Appl. No.: **29/094,624**

The ornamental design for a combined transport protection device and support device for signal transmitting equipment, as shown and described.

(22) Filed: **Oct. 6, 1998**

DESCRIPTION

(30) **Foreign Application Priority Data**

Apr. 6, 1998 (SE) 98-0784

(51) **LOC (7) Cl.** **12-02**

FIG. 1 is a perspective view of a combined transport

(52) **U.S. Cl.** **D34/24; D34/12**

FIG. 2 is a side elevational view thereof.

(58) **Field of Search** D34/12-27, 1,

FIG. 3 is a back elevational view thereof.

D34/5; 280/47.19, 47.17, 47.24, 47.27,

FIG. 4 is a front elevational view thereof;

47.35, 79.11

FIG. 5 is a top elevational view thereof; and,

(56) **References Cited**

FIG. 6 is a bottom elevational view thereof.
